F. B. FREEMAN,
MACHINE FOR REINFORCING INSOLES,
APPLICATION FILED NOV. 29, 1915.

1,209,278.

Patented Dec. 19, 1916.

UNITED STATES PATENT OFFICE.

FRANK B. FREEMAN, OF DAYTON, KENTUCKY, ASSIGNOR TO THE KROHN FECHHEIMER COMPANY, OF CINCINNATI, OHIO, A CORPORATION OF OHIO.

MACHINE FOR REINFORCING INSOLES.

1,209,278.

Specification of Letters Patent. Patented Dec. 19, 1916.

Application filed November 29, 1915. Serial No. 63,918.

To all whom it may concern:

Be it known that I, FRANK B. FREEMAN, a citizen of the United States, and a resident of Dayton, in the county of Campbell and 5 State of Kentucky, have invented certain new and useful Improvements in Machines for Reinforcing Insoles, of which the following is a full, clear, and exact description, reference being had to the accompanying 10 drawings, forming part of this specification.

My invention relates to machines for pressing in the canvas of reinforced insoles around the upturned lip thereof. In machines of this character, it is very desirable 15 to have a light structure, silently running and easy to operate. Also in tucking the canvas around the upturned lips of insoles, it is desirable to have not only one movable tool working up against the insole lip on the 20 inside, but also to have a tool or tools working on the outside of the lip also. In machines of this character, in the past it has been found difficult to provide the proper motion for the pressing-in tools without 25 complicated mechanism, and it is desirable to simplify the method of obtaining this motion.

Accordingly it is the object of my invention to provide a machine of the character 30 mentioned which is light and silent running.

It is also an object of this invention to provide for the motion of the pressing tool by a simple vibrator in combination with 35 a cam and spring, thereby greatly simplifying the mechanisms of the past.

Again it is the object of this invention to provide for oscillating tools on the outside of the insole lip, said tools being actuated by the same device which moves the inner tool, the motion of these outer tools being such as to coöperate with the inner tool to accomplish the most effective and 40 smooth pressing down of the canvas around the inside lip.

These objects, and other advantages to be noted as the description proceeds, I accomplish by that certain construction and arrangement of parts to be hereinafter more 45 specifically pointed out and claimed.

In the drawings, Figure 1 is a top plan view of the machine, with the operating

mechanism removed. Fig. 2 is a side elevation thereof. Fig. 3 is an enlarged side elevation of the pressing-in tool. Fig. 4 is a perspective view of the lower plate for abutting the edge of the insole and guiding the same through the machine. Fig. 5 is a diagrammatic plan view showing the coöperating action of the various pressing or tucking-in tools.

The base plate 1 of the machine is mounted on a standard 2 of suitable character, which is preferably low so that the machine can be set up on a working table or 5 bench. This base plate has a T-slot in its upper surface; said plate having the cross portion 3 of the slot extending through the plate from one side to the other, and the longitudinal portion 4 of the slot extending 10 forwardly to the front of the plate. On this base plate is mounted the top plate 5 which supports a vertical shaft 6. This shaft is caused to rotate by any desired mechanism such as the pulleys and belt 7 and 8 respectively, although this is not an essential part 15 of my invention.

Mounted in the T-shaped slot between the two members is a T-shaped bar, having the lateral member 9 and the forwardly extending member 10. The bar has a longitudinal slot 11 in it, and in this slot is set a square block 12, having a hole 13 in it to receive the eccentric stud at the end of the shaft 6. It can thus be seen that as the shaft revolves, the T-bar will be caused to reciprocate or vibrate in the slot. On an extension 14 from the top member is mounted an anti-friction roller 15, which contacts with the upper surface of the T-bar through a slot 16 in the said top member. Mounted on the forwardly extending end of the bar member 10 is a block 17, which has pivoted in a groove in its outer face the pressing-in tool 18. This block has also a transverse groove 19 in its rearward face, whereby it is mounted over the end of the T-bar, a removable screw 20 or the like serving to secure the mounting.

A plate 21, having a cam edge 22, is 20 mounted on top of the extension 14, and the roller 22 on the upper end of the tool 17 is spring-held against this edge by the spring 23. This cam edge 21 slants from front to

rear, and it is plain that as the T-bar member 10 is vibrated, the tool will move in a diagonal path toward the body of the machine and away from it each time the bar vibrates. The tool 17 has a claw 24 at its lower end, and this claw is adapted to engage on the inside of the lip 25 and press or iron the canvas 26 of the insole firmly into the crotch of the lip. Extending down from the rear end of the tool holding member 16 is a plate 27, having a sloping outer face 28 that engages the outside of the insole lip, thereby backing up the movement of the claw 24, and imparting the proper slant to the insole lip. There are thus two ironing or pressing members, one moving toward the other, and the canvas is not hammered against the lip but is smoothed and ironed into place.

26 Mounted on the under side of the base portion 1 of the machine is a plate 29, having a beveled edge 30, which extends out so as to contact with the shoulders of the lip 25. This plate serves as a guide for the insole through the machine, and is adjustably mounted by means of the slots 32 and the screws 33 for securing it to the machine base.

30 Mounted on an arm 34 extending forwardly from the standard to the machine is a journal member 35. A shaft 36 extends through this journal member and is pushed upwardly in said member by a spring 37 housed within the journal. At the lower 35 end of this shaft are nuts 38, limiting the upward movement of the shaft and a hook 39 engaging with a foot treadle. On top of the shaft is a table 40, which extends up beneath the tool 17, and over this table the insole is passed during the operations of the machine. The plate 29 also extends out over this table, and it is obvious that for inserting the work in the machine it is not necessary to tilt any part of the machine, but 40 only to pull down the table, which is a very easy operation.

Extending outwardly from the two sides of the lateral member 9 of the T-bar are pins 41, having cam ends 42. These cam ends, as the bar is vibrated, contact with pivotally mounted rods 43, 43, which are carried by member 44 pivoted at 44^a to the sides of the base 1, and are held downwardly by springs 45. These rods bend inwardly 45 and downwardly at 46 to a position, one on one side and one on the other side of the plate 27 of the tool holder. As the bar is vibrated, first one and then the other of the rods 43 are tipped at the rear, causing the forward ends 46, 46, to come down and contact with the outer edge of the insole, just outside of the lip thereof.

The operation of the machine is then as follows. The T-bar is caused to vibrate by 60 rotating the shaft 6, the table is lowered and

an insole with canvas affixed to it is inserted at the side of the machine. The end 30 of the plate 29 then serves as a guide at the edge of the insole, and the plate 27 rests against the outside of the lip. The first 70 member to strike the insole in any sequence of operations is the rod 43 nearest the operator, which pulls the canvas well over the lip of the insole. The claw 24 then comes in against the inside of the insole, against 75 the edge 28 of the plate 27 and simultaneously the other outside rod 43 comes down and cooperates with the claw in firmly tamping the canvas down around the lip.

The forward movement of the claw in a diagonal line serves to feed the insole over the table, and it is unnecessary to provide means to revolve the table. The two outer tamping members serve the purpose of completely smoothing and pressing down the 85 canvas on the outside of the lip. For insoles having the lip at different positions in from the edge of the leather portion of the insole, the plate 29 is to be shifted so as to change the position of the outer abutment. 90

Various modifications are possible in this machine without departing from the spirit of the invention, and it is not desired, by reason of the omission of mention of such modifications, to limit the claims that follow beyond the full scope of equivalents, where the wording of the claims does not negative such an interpretation. 95

Having thus described my invention, what I claim as new and desire to secure by Letters Patent, is:—

1. In a machine of the character described, the combination with operating mechanism, a vibrating member, a pivoted lip engaging tool on said member, an abutment arranged with the surface thereof at an acute angle to the line of vibration of said member, and means for maintaining one end of said tool against said abutment, to give its working end a diagonal movement toward the lip of an insole being operated upon. 105

2. In a machine of the character described, the combination with operating mechanism, a horizontal vibrating member actuated thereby to vibrate horizontally, a work support, a pivoted tool on the vibrating member to press the canvas around the inner side of the lip of a reinforced insole, said tool being located over the work support, and means for giving an angular movement with relation to the work to the one end of the tool to cause the other end to have a diagonal movement toward the lip and along the face of the insole, to press down the canvas, and feed the insole over the table. 115

3. In a machine of the character described, the combination with an operating mechanism, a vibrating member actuated 120

- thereby to vibrate horizontally, a pivoted lip-engaging tool on said member resting in contact with the work, and means for giving an angular movement, at an acute angle to the lip of an insole being operated upon, to the one end of the tool, to cause the other end to describe a like path, for the purpose described.
4. In a machine of the character described, 10 in combination with an operating mechanism, a tool for pressing the canvas around the inside of an insole lip, means maintaining said tool against the canvas surface of the insole and for intermittently bringing said tool into contact with such lip on the inside, and a tool for intermittently contacting with said lip on the outside simultaneously with the other tool.
5. In a machine of the character described, 20 in combination with an operating mechanism, a tool for pressing the canvas around the inside of an insole lip, means for intermittently bringing said tool into contact with such lip, and a tool for contacting with said lip on the outside simultaneously with the other tool, and another tool for intermittently contacting with the outside of the lip prior to the contact of the other tools.
6. In a machine of the character described, 30 in combination with a vibrating member, a tool for pressing the canvas around the inside of an insole lip, means for intermittently bringing said tool into contact with such lip, and a tool for contacting with said lip on the outside simultaneously with the other tool, and another tool for intermittently contacting with the outside of the lip prior to the contact of the other tools.
7. In a machine of the character described, 40 the combination with operating mechanism, a vibrating member, a pivoted tool removably mounted on said member, an abutment at an acute angle to the line of vibration, and means for maintaining said tool against the angular abutment, to give its working end a diagonal movement toward the lip of an insole being operated upon, for the purpose described.
8. In a machine of the character described, 50 in combination with a vibrating member, a pivoted tool on said member, held in contact with the insole, means for causing said tool to describe a path at an acute angle to an insole lip and to intermittently contact with the inside of the insole lip, and a fixed abutment for the outer side of the insole lip mounted on said vibrating member to vibrate in contact with the insole, for the purpose described.
9. In a machine of the character described, 60 in combination with a vibrating member, a pivoted tool on said member, means for causing said tool to describe a path at an acute angle to an insole lip and to intermittently contact with the inside of the insole lip, a fixed abutment for the outer side of the insole lip mounted on said vibrating member, and a pair of tools arranged to contact with the outside of the insole lip. 70
10. In a machine of the character described, 75 in combination with a vibrating member, a pivoted tool on said member, means for causing said tool to describe a path at an acute angle to an insole lip and to intermittently contact with the inside of the insole lip, a fixed abutment for the outer side of the insole lip mounted on said vibrating member, a pair of tools arranged to contact with the outside of the insole lip, 80 and means for causing them to operate, one out of unison and one in unison with the pivoted tool.
11. In a machine of the character described, 85 in combination with a vibrating member, a pivoted tool on said member, means for causing said tool to describe a path at an acute angle to an insole lip and to intermittently contact with the inside of the insole lip, a fixed abutment for the outer side of the insole lip mounted on said vibrating member, a pair of tools arranged to contact with the outside of the insole lip, 90 and means on the vibrating member for operating the said pair of tools. 95
12. In a machine of the character described, 100 in combination with a vibrating member, a pivoted tool on said member, means for causing said tool to describe a path at an acute angle to an insole lip and to intermittently contact with the inside of the insole lip, a fixed abutment for the outer side of the insole lip mounted on said vibrating member, and a pair of tools arranged to contact with the outside of the insole lip, 105 said vibrating member comprising a T-bar having the pivoted tool and fixed abutment on its forward end and means on its lateral end for operating the said pair of tools.
13. In a machine of the character specified, 110 the combination with a tool for ironing canvas against an insole lip, of an operating device for said tool, said operating device adapted to vibrate said tool in a direction diagonal to the insole lip, said operating means being adapted to vibrate in a plane parallel to the surface of the insole. 115
14. In a machine of the character specified, 120 the combination with a tool for ironing canvas against an insole lip, of an operating device for said tool, said operating device adapted to vibrate said tool in a direction diagonal to the insole lip, said operating means being adapted to vibrate in a plane parallel to the surface of the insole, and another tool mounted on the operating device, said latter tool being rigidly mounted thereon to vibrate parallel with said lip and on the opposite side thereof from the first tool. 125

15. In a machine of the character described, in combination with a tool located on each side of an insole lip, means for imparting a movement of the one tool parallel to the line of feed of the work, a means for imparting a movement to the other tool diagonal to the line of feed, and means for

maintaining both tools in contact engagement with the work whereby the tools are brought together for a slight feeding movement only at the end of each diagonal movement of said other tool. 10

FRANK B. FREEMAN.
